(57) **CLAIM**

The ornamental design for a power supply, as shown and described.

DESCRIPTION

FIG. 1 is a top, front and right side perspective view of a power supply showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,
FIG. 10 is an enlarged view of portion 10 in FIG. 1.

The broken lines in the drawings illustrate portions of the power supply which form no part of the claimed design.
The oblique shade lines in the drawings represent reflective surfaces.

1 Claim, 10 Drawing Sheets
